CHILDREN'S ELEVATED PLAYHOUSE

Thomas N. De Pew and Ferris Andrew Bell, St. Louis County, Mo., assignors to Arrowhead Products, Inc., St. Louis, Mo., a corporation of Arkansas

Filed Feb. 12, 1962, Ser. No. 68,760

Term of patent 14 years

(Cl. D34—15)

We claim:

The ornamental design for a children's elevated playhouse, as shown and described.
